FREDERIC E. KIP, OF MONTCLAIR, NEW JERSEY

GOLF CUP

Application filed November 7, 1929. Serial No. 405,401.

My invention relates to golf cups. So far as I am aware, golf cups as heretofore made, have had but a single point of support for the staff, the result being that the staff assumes an inclined position which is annoying to players and requires that the staff be moved to a vertical position before a putting shot is made.

One object of my invention is to provide a support for the staff having a plurality of points of support against vertical displacement so that the staff will always be maintained in vertical position.

Also, so far as I know, the pan attached to the staff has had no means for retaining the balls when the staff is lifted from the cup, with the result that the balls roll from the pan and are apt to fall back into the cup making it necessary to lift them out by hand. Another object of my invention is to provide a pan of such form that the balls will be retained thereon until after the staff has been lifted and moved away from the cup thereby avoiding the likelihood of the balls falling back into the cup.

These and other features of my invention will be understood by reference to the accompanying drawings in which Fig. 1 is a vertical section with the staff and flag in elevation; Fig. 2 a top view of the centering sleeve upon which the pan is adapted to rest; and Figs. 3 and 4 are views of modifications which may be employed.

Referring to Fig. 1 the numeral 1 designates a cup of standard depth and diameter adapted to be placed in an opening in the ground. Secured to the inner wall of the cup is a member 2 constituting a seat for the pan 3 secured to the staff 4. The member 2 has a depending cylindrical flange 5 which I term a centering sleeve. It extends to substantially the plane of the lower end of the cup. As shown in Fig. 2 this member is formed with a series of openings 2' to permit the escape therethrough of water.

Fitted within the sleeve 5 is a bushing 6 having a central bore, the upper end of which is frusto-conical to provide a seat for a cone-shaped collar 7 secured to the staff immediately below the pan 3. The latter has an up-

wardly and outwardly extending flange 3' by which the balls, one of which is indicated at 8, will be retained when the staff is lifted from the cup.

The bushing 6 may extend below the cup, as indicated in the drawings. At least it should be of such length that a sufficiently stable support for the staff will be provided to maintain the staff always in a vertical position. The staff carries the usual flag 9.

In Fig. 3 the collar 10 attached to the staff immediately below the pan is made cylindrical instead of cone-shaped as in Fig. 1. The bushing 11 is also modified by making the upper part of its central bore 12 cylindrical, and of a diameter to receive the collar 10. The bore of the lower part of the bushing is of such diameter as to receive the lower end of the staff without binding, as in Fig. 1.

Fig. 4 illustrates another modification in which the centering sleeve 13 has a greater degree of inclination than in Figs. 1 and 3 and is formed with a dependent cylindrical flange 13' of such internal diameter as to receive the flange 14' of the pan 14 when the staff is placed within the cup.

Near the lower end of the cup is secured a second centering sleeve 15 having a cylindrical flange 15' through which the lower end of the staff is passed.

It will thus be seen that in all of the forms described, the lower end of the staff will be held against lateral displacement so that the staff will always be maintained in a vertical position.

In Fig. 1 the section of the staff below the pan will be in contact with the walls of the bore of bushing 6 thus having a plurality of points of support.

In Fig. 3 one point of support is afforded by the seating of the cylindrical collar 10 in the enlarged portion 12 of the bore of bushing 11, while a second point is afforded by the lower end of the staff being in contact with the wall of the smaller bore. In Fig. 4 the flange 14' is seated within the cylindrical collar flange 13' of the centering sleeve 13, and the lower end of the staff within the flange 15' of sleeve 15.

By providing the pan with a retaining

flange, the balls will be prevented from falling or rolling off until after the staff has been lifted from the cup. The balls may then be thrown off on the green away from any possibility of having them falling back into the cup.

The several parts of my improved cup are simple in construction and easily assembled. In actual use it has been accepted by players as meeting a long-felt want as it avoids the necessity of the player placing and having the staff held in a vertical position while making a putting shot, and avoids the annoyance of the golf balls falling back again into the cup after they have been withdrawn therefrom by the elevation of the staff, and avoids the player having to stoop down and pick the balls out by hand.

The cup being of small diameter it is often difficult and always tiresome to secure the ball by the hand and withdraw it out of the cup.

What I claim is:

In combination, a putting-cup, a member secured to the inner wall thereof, a staff and a pan secured thereto, said member constituting a seat for said pan and having a depending cylindrical flange extending to substantially the plane of the lower end of the cup, a collar on said staff below the pan, and a bushing within said flange, said bushing having a seat to receive the staff collar.

Signed at New York city, in the county of New York and State of New York, this 18th day of October A. D. 1929.

FREDERIC E. KIP.
